UNITED STATES PATENT OFFICE

149,509

DESIGN FOR AN AMUSEMENT APPARATUS

Clare G. Meyer, Chicago, Ill., assignor to Exhibit Supply Company, Chicago, Ill., a corporation of Illinois

Application December 20, 1946, Serial No. 135,656

Term of patent 7 years

(Cl. D34—5)

To all whom it may concern:

Be it known that I, Clare G. Meyer, a citizen of the United States and a resident of Chicago, in the county of Cook and State of Illinois, have invented a new, original, and ornamental Design for an Amusement Apparatus, of which the following is a specification, reference being had to the accompanying drawing, forming a part thereof, and in which:

Fig. 1 is a perspective view of an amusement apparatus showing my new design.

Fig. 2 is a side elevational view of the same.

I claim:

The ornamental design for an amusement apparatus, as shown.

CLARE G. MEYER.
